UNITED STATES PATENT OFFICE.

DENIS WILLIAM DALEY, OF PARKERSBURG, WEST VIRGINIA.

SUPPORT FOR MOLDBOARDS.

1,149,637.

Specification of Letters Patent. Patented Aug. 10, 1915.

Application filed January 26, 1914. Serial No. 814,377.

To all whom it may concern:

Be it known that I, DENIS WILLIAM DALEY, a citizen of the United States, residing at Parkersburg, in the county of Wood and State of West Virginia, have invented new and useful Supports for Moldboards, of which the following is a specification.

My invention generically appertains to mold forms for the construction of concrete walls and the like, but more essentially to that class of form adapted to be constructed in courses.

One object of my invention resides in providing a mold form for concrete walls and the like, wherein the mold boards comprising the form are constructed in courses, one above the other, and may be removed from the set or hardened portion of the concrete wall and disposed upon the uppermost courses of boards so as to form a continuation of the mold form as the construction of the wall progresses upwardly.

A further object of this invention resides in providing a series of supports having means connected thereto and projecting laterally therefrom for coöperation with certain other means secured to mold boards whereby the latter may be properly supported in vertical position.

Another object of my invention lies in providing a novel means for bracing the mold board against the lateral thrust of the end construction.

Another and still further object of this invention resides in so constructing the mold form that the lowermost course of mold boards forming the latter, may be readily removed without disturbing the course of mold boards disposed above it.

With these and other objects in view, my invention consists of certain novel details of construction, arrangement, and combination of parts to be more particularly set forth and claimed.

In the accompanying drawings in which corresponding parts are indicated by similar reference numerals, Figure 1 is a fragmentary perspective view, partly in section, illustrating a partially constructed wall having my improved mold boards removed and disposed upon the uppermost course thereof; Fig. 2 is a horizontal section taken on the line 2—2 of Fig. 1; Fig. 3 is a fragmentary perspective view of one of the mold boards illustrating the latter in connection

with my improved bracket for supporting the same; Fig. 4 is a fragmentary perspective view of a modified form of my improved mold illustrating the latter in connection with the partially constructed wall; Fig. 5 is a transverse vertical section of the form shown in Fig. 4; Fig. 6 is a perspective view of a modified form of mold bracket; Fig. 7 is a transverse vertical section taken on the line 7—7 of Fig. 5; Fig. 8 is a horizontal section taken on the line 8—8 of Fig. 7; Fig. 9 is a side elevation partially in section illustrating a modified form of the means for preventing lateral movement of the mold board; Fig. 10 is a horizontal section taken on the line 10—10 of Fig. 9; Fig. 11 is a transverse vertical section illustrating a modified form of supporting bracket for the mold board, and Fig. 12 is a horizontal section taken on the line 12—12 of Fig. 11.

Heretofore in the construction of concrete walls it has been customary to either build the form to the proposed height of the desired wall, or else construct the forming courses as the wall progresses upwardly, in the latter case, however, the boards used in constructing the lower portion of the wall are left in place and new boards added to those to increase the height of the form. This has been found disadvantageous, however, because, in the first place, it required quite an outlay of lumber in order to provide the necessary mold board, and secondly, that after the wall had been constructed, the boarding used was what might be termed as dead lumber, and had to be sold at a loss to the party constructing the wall. To this end I propose to provide a form which reduces the number of parts required to produce a wall of a given height, inasmuch as it enables the lower mold boards to be removed after the concrete has set or hardened, and used in forming the upper portion of the wall, furthermore, the entire form may be continually reused for other construction work, as will be readily understood without further description.

In view of the foregoing, I propose to provide a plurality of angular standards 1 which are arranged in pairs, the members of each pair being oppositely disposed and situated in spaced relationship, as clearly shown in Fig. 1. Mounted upon each of the standards 1 are a series of brackets 2 which are formed in two sections 3 and 4 respec-

tively, the latter being twisted intermediate its ends to a plane substantially at right angles to that of the former. Section 4 of the brackets 2 has its outer end extended laterally as at 5, and provided with a centrally arranged aperture 5' for a purpose hereinafter to be set forth. Also projecting laterally from the section 4 contiguous to the extremity 5 thereof, is a tongue 6 which 10 coöperates with said extremity 5 to form a seat adapted to engage with each of said standards. In order that the brackets may be permanently maintained in their adjusted positions, I provide a set screw 7 which passes through the openings 5' and engages the outer surfaces of the standards to secure said brackets in their proper position and relation. The outer extremity of section 3 of the brackets 2 is provided with 20 the oppositely projecting flanges 8 which, when the mold boards 9 are arranged edge-wise one above the other, project in the channel 10 formed in the channel irons 11 which are disposed upon the longitudinal 25 edges of said mold boards 9 and securely support the latter in proper position to form a unitary construction, as will be readily understood without further description. I have found in actual practice, however, that 30 it may sometimes be desirable to replace the angular standards 1 with the annular posts 12 which latter are provided at predetermined points thereon with the cross shaped openings 13 which receive the reduced extremity 14 having the enlarged head 15 of 35 the mold board support bracket 16. From this construction it will be seen that when the enlarged head 15 of bracket 16 is passed through the enlarged portion of opening 13 40 and projected downwardly into the reduced portion thereof, said head will be locked in position and consequently the bracket 16 cannot become disengaged. Furthermore, to increase the stability of bracket 16, I propose 45 vide the inner surface of post 12 on opposite sides of the reduced portion of the cross shaped openings 13 therein with studs 15' which it will be seen frictionally engage the inner edge of the enlarged portion 15 of 50 the bracket and assist in maintaining the latter in proper rightangular relation to the post 12.

The outer extremities of brackets 16 are provided with oppositely projecting flanges 55 18 which enter the channels 10 of the mold boards and support the same in position, as described in connection with the first mentioned brackets. Owing to the severe lateral thrust placed upon the mold boards 9, 60 I propose to strengthen the same by placing a series of blocks 19 at predetermined points on the outer surfaces of each of said boards, which blocks engage the arcuate extremities 65 of the bracing rods 20, said rods having reduced ends 21 which project within suitable

openings 22 formed in post 12, which construction provides an absolute preventive against all lateral movement on the part of said mold boards 9.

In lieu of the bracket 16 and means for 70 bracing the same as just described, I may substitute the brackets 28 which latter are hingedly connected as at 29 intermediate their ends, the hinged connection being so arranged that each pair will open oppositely. 75 By hingedly connecting the brackets in this manner, the same are formed in two sections 28' and 28'', the latter has its outer extremity threaded as at 30, and passed through the registered openings 31 so as to project 80 from the opposite side of the post 12 and to receive nut 32 which coöperates with the nut 33 to lock the brackets securely to the post. The outer extremities of the sections 28' are also provided with oppositely projecting 85 flanges 32' which project into the channels 10 formed in the mold boards 9 and support the latter in operative position, as clearly shown in Fig. 11. In place of the blocks 19 and the strengthening rods 20, I may substitute the wedge-shaped blocks 23 and the bracing rods 25 which latter have an eccentrically mounted wheel 24 at one end thereof to coöperate with the wedge-shaped blocks 23; the other extremity of said bracing arms 25 being reduced as at 26 to project within suitable openings 27 formed in post 12. Thus it will be seen that I have provided a mold form which may be readily transferred from place to place and reused 100 when necessary, as well as one so constructed that the mold boards constituting the form may be removed during the construction of the wall or the like, and reused in the further construction thereof, which consequently greatly reduces the cost in erecting concrete structures, and is in every way far superior to the molds now in use. 105

I claim:

1. The herein described mold form comprising a plurality of oppositely disposed standards arranged in vertical and spaced relation, of a series of mold board supporting members detachably connected at one of their extremities to said standards with 110 their free ends projected laterally therefrom, said members being arranged in vertically spaced relation upon said standards, mold boards disposed between said members and having channels formed in the longitudinal edges thereof, oppositely projecting flanges integrally formed on the free ends of 115 said supporting members and having their edges disposed in horizontal planes whereby to project within the channels formed in 120 said mold boards and support the latter in edgewise position substantially as and for the purpose set forth.

2. The herein described mold form comprising a plurality of oppositely disposed 130

- standards vertically arranged in spaced relation, a series of mold supporting members detachably connected at one of their extremities to said standards and adapted to project laterally therefrom, said members having one section thereof disposed in a horizontal plane, mold boards disposed intermediate said members and having their longitudinal edges channeled, and oppositely projecting flanges integrally formed on the free ends of the horizontally disposed sections of said mold board supporting members whereby to project within the channels formed in said mold boards substantially as and for the purpose set forth. 70
- 5 3. The herein described mold form comprising a plurality of oppositely disposed standards vertically arranged in spaced relation, a series of mold board supporting members disposed in vertically spaced relation upon said standards and projecting laterally therefrom, said members including a vertically and a horizontally disposed section, the former having its free extremity 80
- 10 projecting laterally and provided with a centrally arranged opening, a tongue integrally formed on said section and projecting in parallel and spaced relation to said extremity whereby to form a seat to engage one edge of said standard, an adjusting screw extending through the opening formed in said extremity to coact with said standard and maintain the supporting member in adjusted position, mold boards 85
- 15 disposed intermediate the supporting members and having the longitudinal edges thereof channeled, oppositely projecting flanges integrally formed on the free ends of said horizontally disposed section of the 90
- 20 supporting members and adapted to project within channels formed in said mold boards substantially as and for the purpose set forth. 95
4. The herein described mold form comprising a series of oppositely disposed standards vertically arranged in spaced relation, a plurality of mold board supporting members arranged in vertically spaced relation on said standards, each of said 100
- 25 members having one extremity provided with an integrally formed clamp for detachable engagement with said standards, mold boards disposed intermediate said supporting members and having channels 105
- 30 formed in their longitudinal edges, and means on the free ends of said supporting members to project within said channels substantially as and for the purpose set forth. 110
5. The herein described mold form comprising a series of oppositely disposed standards, vertically arranged in spaced relation, a plurality of mold board supporting members arranged in vertically spaced relation upon said standards, each of said 115
- 35 members having one end provided with an integrally formed clamp for detachable engagement with said standards, mold boards disposed intermediate the supporting members and having channels formed in their longitudinal edges, and integrally formed flanges on the free ends of said supporting members to project within said channels substantially as and for the purpose set forth. 120
- 40 6. The herein described mold form comprising a plurality of oppositely disposed standards vertically arranged in spaced relation, a series of mold board supporting members having one of their extremities detachably connected to said standards, said members being arranged in vertically spaced relation upon the latter and projecting laterally therefrom, mold boards disposed intermediate said members, channel irons disposed upon the longitudinal edges of said mold boards, and oppositely projecting flanges integrally formed on the free ends of said supporting members and adapted to coact with said channel irons substantially as and for the purpose set forth. 125
- 45 7. The herein described mold form comprising a plurality of oppositely disposed standards vertically arranged in spaced relation, a series of mold board supporting members disposed in vertically spaced relation upon said standards, each of said members having one extremity provided with an integrally formed laterally offset clamp, whereby said members may be detachably connected with said standards and project laterally therefrom, mold boards disposed intermediate said members, channel irons disposed upon the longitudinal edges of said mold boards, and integrally formed means carried by the free ends of said supporting members for coöperation with said channel irons substantially as and for the purpose set forth. 130
- 50 8. The herein described mold form comprising a plurality of oppositely disposed standards vertically arranged in spaced relation, a series of mold board supporting members disposed in vertically spaced relation upon said standards, each of said members having one extremity provided with an integrally formed laterally offset clamp, whereby said members may be detachably connected with said standards and project laterally therefrom, mold boards disposed intermediate said members, channel irons disposed upon the longitudinal edges of said mold boards, and oppositely projecting flanges integrally formed on the free ends of said supporting members for coöperation with said channel irons substantially as and for the purpose set forth. 135
- 55 9. The herein described mold form comprising a plurality of oppositely disposed

standards vertically arranged in spaced relation, a series of mold board supporting members disposed in vertically spaced relation upon said standards each of said members comprising a body, the latter being twisted intermediate its ends to form vertically and horizontally disposed sections, the former having its free extremity extended laterally and provided with a centrally arranged aperture, a tongue normally formed on said section and projecting in parallel and spaced relation to said extremity whereby to coöperate with the latter and produce a seat, a set screw adapted to project through the aperture in said extremity and co-act with said standards to retain said members in adjusted position, oppositely projecting flanges normally formed on the free extremity of said horizontal section, and mold boards disposed intermediate said members and having means in the longitudinal edges thereof for coöperation with said oppositely projecting flanges substantially as and for the purpose set forth.

10. The herein described mold form comprising a series of oppositely disposed standards vertically arranged in spaced relation, a plurality of mold board supporting members carried by said standards in spaced relation thereon and projecting laterally therefrom, mold boards disposed intermediate said members and having channels formed in their longitudinal edges, means on the free ends of said members to project within said channels, bracing rods projecting from said standards, and means disposed upon the outer surfaces of said boards for coöperation with the free ends of said bracing rods substantially as and for the purpose set forth. 25 30 35 40

In testimony whereof I have hereunto set my hand in presence of two subscribing witnesses.

DENIS WILLIAM DALEY.
